[57] CLAIM

The ornamental design for a combined bottle and cap, as shown and described.

DESCRIPTION

FIG. 1 is front elevational view of a combined bottle and cap showing our new design;

FIG. 2 is a rear elevational view thereof;

FIG. 3 is a side elevational view thereof; and,

FIG. 4 is a top plan view thereof.

The portions of the combined bottle and cap that are not shown in the drawings do not form part of the claimed design.
